DESIGN FOR A PROTECTOR MAT FOR KITCHEN TABLES, STOVES, AND THE LIKE

James R. Caldwell, Wooster, Ohio, assignor to
The Wooster Rubber Company, Wooster, Ohio

Application June 12, 1940, Serial No. 92,953

Term of patent 14 years

To all whom it may concern:

Be it known that I, James R. Caldwell, a citizen of the United States, residing at Wooster, in the county of Wayne and State of Ohio, have invented a new, original, and ornamental Design for a Protector Mat for Kitchen Tables, Stoves, and the like, of which the following is a specification, reference being had to the accompanying drawing, forming part thereof, wherein:

Figure 1 is a top plan view of a protector mat for kitchen tables, stoves, and the like, showing my new design;

I claim:

The ornamental design for a protector mat for kitchen tables, stoves, and the like, substantially as shown.

JAMES R. CALDWELL.
